US0D1084394S

(12) **United States Design Patent** (10) Patent No.: **US D1,084,394 S**
(45) Date of Patent: ** Jul. 15, 2025

(54) **SEQUENCING INSTRUMENT**

(71) Applicant: **BGI SHENZHEN**, Shenzhen (CN)

(72) Inventors: **Wu Zhan**, Guangdong (CN); **Quanxin Yun**, Guangdong (CN); **Zhentao Zhao**, Guangdong (CN); **Lin Li**, Guangdong (CN); **Yao Wang**, Guangdong (CN); **Lei Yu**, Guangdong (CN); **Yuxiang Li**, Guangdong (CN); **Yuliang Dong**, Guangdong (CN); **Wenwei Zhang**, Guangdong (CN); **Yuning Zhang**, Guangdong (CN); **Xun Xu**, Guangdong (CN)

(**) Term: **15 Years**

(21) Appl. No.: **35/522,201**

(22) Filed: **Aug. 2, 2024**

(80) **Hague Agreement Data**

Int. Filing Date: **Aug. 2, 2024**

Int. Reg. No.: **DM/239659**

Int. Reg. Date: **Aug. 2, 2024**

Int. Reg. Pub. Date: **Sep. 6, 2024**

(51) LOC (15) Cl. **24-02**

(57)

CLAIM

The ornamental design for a sequencing instrument as shown and described.

DESCRIPTION

1. Sequencing instrument

1.1 : Perspective

1.2 : Perspective

1.3 : Front

1.4 : Back

1.5 : Left

1.6 : Right

1.7 : Top

1.8 : Bottom

1.9 : Perspective view shown in an open state

The broken lines shown in the figures depict portions of the sequencing instrument that form no part of the claimed design.

1 Claim, 9 Drawing Sheets
